Primary Examiner — Mitchell Siegel(74) *Attorney, Agent, or Firm* — Banner & Witcoff, Ltd.(57) **CLAIM**

The ornamental design for a golf club head for a putter, as shown and described.

DESCRIPTION

FIG. 1 is a rear perspective view of a golf club head for a putter showing our new design;

FIG. 2 is a bottom perspective view thereof;

FIG. 3 is a front view thereof;

FIG. 4 is a rear view thereof;

FIG. 5 is a heel end view thereof;

FIG. 6 is a toe end view thereof;

FIG. 7 is a top view thereof; and,

FIG. 8 is a bottom view thereof.

The broken lines immediately adjacent to the shaded area represent unclaimed boundaries of the design. The unshaded regions within or adjacent to the shaded area form no part of the claimed design. The broken lines showing the remainder of the golf club are for environmental purposes only and form no fan of the claimed design.
